UNITED STATES PATENT OFFICE

106,059

DESIGN FOR AN ARTIFICIAL FISH BAIT

Carl S. Raymond, Flint, Mich.

Application January 22, 1937, Serial No. 67,239

Term of patent 14 years

To all whom it may concern:

Be it known that I, Carl S. Raymond, a citizen of the United States, residing at Flint, county of Genesee, State of Michigan, have invented a new, original, and ornamental Design for an Artificial Fish Bait, of which the following is a specification, reference being had to the accompanying drawing, forming part thereof.

Fig. 1 is a top plan view of an artificial fish bait showing my new design.

Fig. 2 is a side elevation of the bait shown in Fig. 1, with the hook and connecting link omitted.

I claim:

The ornamental design for an artificial fish bait, as shown.

CARL S. RAYMOND.
